TRAFFIC STRIPE MACHINE

Samuel J. Dalton, Jackson, Miss.

Application April 10, 1935, Serial No. 15,685

2 Claims. (Cl. 91—18)

This invention relates to a machine especially adapted for placing markings or stripes on road or street surfaces to indicate traffic lanes or other traffic regulations and has for the primary object the provision of a device of this character which will during its movement over a road or street clean a selected area of the surface of said road and apply thereto bituminous material and an aggregate, sand stone, gravel or slag, and roll or compress said materials to form the desired marking which may be seen for a considerable distance both day and night and is durable and not easily defaced, marred or worn off by traffic.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a side elevation illustrating a machine constructed in accordance with my invention.

Figure 2 is a top plan view illustrating the same.

Figure 3 is a front elevation illustrating the device.

Figure 4 is a rear elevation illustrating the device.

This machine is to be propelled or moved over a road surface in any well known manner and consists of a main frame 1 mounted on front and rear wheels 2 and 3. The axle of the front wheels 2 is indicated by the character 4 and is of the steering type actuated through the manipulation of a hand lever 5. The rear axle assembly for the rear wheels 3 is indicated by the character 6 and includes the usual differential which in this case is connected to a shaft 7 extending forwardly from the differential and geared to a power shaft 8. The power shaft is suitably journaled to the main frame 1 and arranged transversely thereof. The power shaft 8 is employed for driving various devices mounted upon the main frame by the forward motion of the machine over the road.

Mounted upon the forward portion of the main frame 1 is a tank or kettle 9 to receive bituminous or other similar materials and the latter is kept at a desired temperature by heat derived from a suitable burner 10 supplied with liquid fuel from a supply source 11 mounted on the frame 1. A pump 12 of any desired construction is mounted in the tank or kettle 9 and its intake has a pipe

13 which extends into the bituminous or like material in the tank or kettle while the outlet of the pump is equipped with a pipe 14 extending downwardly and rearwardly with respect to the tank or kettle and carries at its lower end a nozzle 15 located in close proximity to the road surface. The pump is driven by drive shaft 8 by a sprocket chain 16 and sprocket gears 17.

Rotatably supported by the frame 1 forwardly of the nozzle 15 is a brush or broom 18 normally 10 contacting the road surface and which may be raised from the road surface by a hand lever 30. The brush or broom is rotated by the drive shaft 8, the latter being connected to the brush or broom by a sprocket chain 19 and sprocket 15 gears 20.

A comparatively large container 21 is mounted upon the rear portion of the frame 1 in which sand, stone, gravel, slag or like material may be placed. The container 21 is in communication 20 with the worm type conveyor 22 having the discharge end 23 located rearwardly of and in alignment with the nozzle 15. The conveyor is connected to the drive shaft 8 by a sprocket chain 24 and sprocket gears 25.

An operator's seat 26 is carried by the container 21 and is located adjacent the steering lever 5. Secured to the frame 1 rearwardly of the conveyor 23 is a spreader 27 spaced a desired distance from the surface of the road.

In operation, the machine is moved forwardly over a road in any desired manner and an area of the surface of the road or street has loose materials removed therefrom by the brush or broom 18. The bituminous material is discharged 35 by the nozzle 15 rearwardly of the brush or broom to form a stripe or marking of a desired width. The aggregate or mineral material in the container 21 is discharged onto the bituminous material on the road by the worm conveyor 23. The 40 aggregate or mineral material is evened by the spreader 27. One of the rear wheels 3 is disposed in alignment with the spreader 27 and is in the form of a roller for the purpose of rolling the aggregate or mineral material into the bituminous material. Thus it will be seen that a very 45 efficient marking is provided on the surface of the roadway easily and quickly with a minimum employment of manual labor and is capable of withstanding severe wear from traffic and may 50 be seen or observed from a considerable distance both day and night.

A water supply tank 28 is carried by the container 21 and has a discharge nozzle 29 disposed over the roller type rear wheel of the machine 55

for the purpose of keeping said wheel moistened to prevent the materials deposited on the surface of the road or street from adhering thereto. The water may be controlled through the nozzle in 5 any desired manner.

Having described the invention, I claim:

1. A machine comprising a portable frame, a tank or kettle mounted on the frame for containing and heating bituminous material, a rotatable brush or broom carried by the main frame to engage the surface of the road to clean an area of the surface of said road, a pump connected in the tank or kettle to obtain bituminous material therefrom, a discharge nozzle connected 10 to the pump and arranged rearwardly of the brush and in close proximity to the surface of the road to apply the bituminous material in strip formation to the surface of the road, means carried by the frame to apply to the surface of 15 the road within the bituminous material an aggregate or mineral material, and a spreader carried by the main frame to even the aggregate or mineral material deposited on the surface of the road, a roller carried by the main frame and 20 acting as a wheel therefor and to compress the materials deposited on the surface of the road. 25

2. A machine comprising a portable frame, a tank or kettle mounted on the frame for containing and heating bituminous material, a rotatable brush or broom carried by the main frame to engage the surface of the road to clean an area of the surface of said road, a pump connected in the tank or kettle to obtain bituminous material therefrom, a discharge nozzle connected to the pump and arranged rearwardly of the brush or broom and in close proximity to the 5 surface of the road to apply the bituminous material in strip formation to the surface of the road, means carried by the frame to apply to the surface of the road within the bituminous material an aggregate or mineral material, a 10 spreader carried by the main frame to even the aggregate or mineral material deposited on the surface of the road, a roller carried by the main frame and acting as a wheel therefor and to compress the materials deposited on the surface of the road to the 15 surface of the road, and means for applying water to the periphery of the roller to prevent the materials on the surface of the road from adhering to the roller.

SAMUEL J. DALTON. 25
